UNITED STATES PATENT OFFICE.

DAVID FISHER, OF PADEN CITY, WEST VIRGINIA.

DESIGN FOR COMBINATION MATCH AND ASH TRAY.

Application filed May 12, 1924. Serial No. 9,557. Term of patent 7 years.

To all whom it may concern:

Be it known that I, DAVID FISHER, a citizen of the United States, residing at Paden City, West Virginia, have invented a new, original, and ornamental Design for Combination Match and Ash Tray, of which the following is a specification, reference being had to the accompanying drawings, forming a part thereof.

The single figure of the drawings is a perspective view of a combination match and ash tray showing my new design.

I claim:

The ornamental design for combination match and ash tray as shown.

DAVID FISHER.
